(57) **CLAIM**

The ornamental design for a label, as shown and described.

DESCRIPTION

FIG. 1 is a front view of a label showing my new design; and, FIG. 2 is a front view of a second embodiment thereof. Thickness of the label forms no part of the claimed design. The top, bottom, left, right and rear views are omitted as they form no part of the claimed design. The broken lines represent features or structure which form no part of the claimed design.
